UNITED STATES PATENT OFFICE.

ALBERT G. MARKS, OF HOULT, WEST VIRGINIA, ASSIGNOR OF ONE-HALF TO MARCUS C. EITE, OF RIVESVILLE, WEST VIRGINIA.

COMBINED NUT-LOCK AND RAIL-BRACE.

1,228,462.

Specification of Letters Patent. Patented June 5, 1917.

Application filed September 12, 1916. Serial No. 119,707.

To all whom it may concern:

Be it known that I, ALBERT G. MARKS, a citizen of the United States, residing at Hoult, in the county of Marion and State 5 of West Virginia, have invented certain new and useful Improvements in Combined Nut-Locks and Rail-Braces, of which the following is a specification.

This invention contemplates an improved 10 nut lock and rail brace especially designed for use at the joints between the meeting ends of railway rails and has as its primary object to provide a device of this character which may be used in connection with substantially any conventional type of rail and 15 formed to engage the nuts of the bolts connecting the rail ends for locking the said nuts against displacement.

The invention has as a further object to 20 provide a device of this character formed to engage beneath the treads of the rails to overlie the base flanges thereof and about the flanges at their outer extremities for effectually bracing the rails against outward 25 lateral movement and consequently holding the rails of a track against spreading.

And the invention has as a still further object to provide a device of this character which will be simple in construction and 30 which may be easily mounted in position.

Other and incidental objects will appear as the description proceeds and in the drawings wherein I have illustrated the preferred embodiment of the invention and 35 wherein similar reference characters designate corresponding parts throughout the several views.

Figure 1 is a perspective view showing my improved nut lock and rail brace applied 40 at the joint between the meeting ends of coacting railway rails of conventional type, and

Fig. 2 is a sectional view more particularly showing the construction of the device 45 and the manner in which the said device is formed to brace the rails against outward movement.

In order that the construction, mounting and operation of the present invention may 50 be entirely clear, I have shown the device in connection with a joint between the meeting ends of coacting railway rails 10 of conventional type, the said rails being supported upon tires 11. Overlying the rail 55 webs, upon opposite sides thereof, at the

joint between the rails, are fish plates 12 formed to fit beneath the rail treads with the lower edges of the said plates resting upon the base flanges of the rails. Extending through the fish plates and through the rail webs, are a plurality of bolts 13 upon which are fitted nuts 14.

Coming now more particularly to the subject of the present invention, a combined locking and brace member is employed including a body 15 formed to lie upon the base flanges of the rails upon the outer sides thereof, with the said body offset longitudinally to provide a shoulder 16 abutting the said base flanges at their outer edges with the body then extended to form an attaching flange 17 resting upon the adjacent ties 11 of the track. At its inner extremity, the body 15 of the device is bent at substantially right angles to form an upstanding locking flange 18 seating against the adjacent fish plate 12 upon the outer sides of the rails 10 and engaging at its upper extremity beneath the rail treads upon opposite sides of the joint between the rails. The locking flange 18 is, at a plurality of longitudinally spaced points formed with suitable openings to snugly receive the nuts 14 of the bolts 13 and connecting the attaching flange 17 of the device with the adjacent ties 11 of the track, are a plurality of headed spikes or other suitable fastening devices 19.

As may now be pointed out, the device may, of course, be varied in size and proportion according to the character of track rails to which it is to be applied. The locking flange 18 will, as will be observed, securely engage the nuts 14 of the bolts 13 for holding the said bolts against displacement so that I thus provide an effectual nut lock for the said bolts. Moreover, the locking flange 18 of the device is arranged to coöperate with the rail treads so that the device will act as a brace, holding the rails against outward lateral movement and consequently preventing spreading of the rails of a track. In this connection, it is also to be observed that the shoulder 16 of the body 15 will coöperate with the outer edges of the base flanges of the rails for holding the said flanges fixed with respect to each other as regards outward lateral movement. It will therefore be seen that I provide a very simple and efficient construction for 110

the purpose set forth, and a device which may be readily applied to the joints between substantially any conventional type of railway rails.

5 Having thus described my invention, what I claim and desire to secure by Letters Patent is:

The combination with meeting rail ends having fish plates at the joint therebetween 10 with the said rail ends connected by a plurality of bolts extending through the said fish plates, of a combined rail brace and locking member overlying the joint between the said rail ends, said member including a 15 body seating against the outer sides of the base flanges of the rails and offset to pro-

vide a shoulder engaging the adjacent outer edges of the said flanges, the body being thence extended at its outer extremity to form an attaching flange seating upon the 20 rail ties and being bent at its inner extremity to provide an upstanding locking flange seating at its upper and lower margins against the outermost of said fish plates with the upper edge of said flange 25 engaging beneath the rail treads to form a brace therefor with openings formed in the said flange to receive the nuts of the said bolts for locking the nuts thereon.

In testimony whereof I affix my signature. 30

ALBERT G. MARKS. [L.S.]
